CARBURETOR

Augustin M. Prentiss, San Antonio, Tex., assignor to Bendix Stromberg Carburetor Company, South Bend, Ind., a corporation of Illinois

Application January 5, 1931, Serial No. 506,689.

7 Claims. (Cl. 261—34)

This invention pertains to carburetors and more particularly has reference to the control of acceleration pumps therefor in accordance with the temperature of the carburetor.

5 The desirability of regulating the acceleration charge of a carburetor in accordance with the temperature of the carburetor has long been recognized in the art and various schemes have been proposed for this purpose. These have generally taken the form of thermally responsive devices for limiting the stroke of the pump associated with the mechanical hookup between the throttle and pump, or temperature responsive valves for relieving pressure upon the accelerating charge, or by-passing a portion of the charge back to the float chamber in those types of acceleration pumps that are actuated by vacuum.

So far as I am aware, no one has yet devised a system of temperature control for vacuum actuated acceleration pumps by varying the vacuum in accordance with the temperature of the carburetor.

An object of this invention is to devise a carburetor in which the acceleration pump is actuated by a vacuum regulated in accordance with the temperature of the carburetor.

Another object of this invention is to provide a carburetor in which the acceleration pump is operated by a temperature responsive vacuum which is at a maximum when the carburetor is at its lowest working temperature and at a minimum when the carburetor is at its highest working temperature.

Still another object of my invention is to devise a vacuum operated acceleration pump in which the stroke of the pump is regulated by varying the vacuum in accordance with the temperature of the carburetor.

With these and other objects in view which 40 may be incident to my improvements, my invention consists in the combination and arrangement of elements hereinafter described and illustrated in the accompanying drawing in which:

Figure 1 shows in central longitudinal section 45 a carburetor embodying my improvements, and

Figure 2 is a fragmentary sectional view, on an enlarged scale, of the temperature responsive vacuum regulating valve.

In Figure 1, the reference numeral 1 indicates 50 the body of a conventional carburetor comprising the usual air intake 2, mixing chamber 3, and mixture outlet 4 controlled by a throttle valve 5. The main nozzle 6 and idle feed 7 communicate through passageways 9 and 10 and port 11 with a 55 float chamber 12, which is supplied with liquid

fuel through inlet 13 from the main fuel tank (not shown). Float 14 and valve 15 maintain the liquid fuel at a constant level indicated by the line X—X in the well known manner, while a valve 16 seating in port 11 controls the main flow 60 of liquid fuel to nozzle 6 and idle ports 7. The float chamber 12 is closed by a cover 17 to which is integrally attached a cylinder 18 which extends partly into the float chamber 12 and partly above the cover 17 as clearly shown in Figure 1. The 65 top of cylinder 18 abuts against a projection 19 carried by the body 1 of the carburetor adjacent the mixture outlet 4, and communicates with the mixture outlet 4 and mixing chamber 3 (when throttle 5 is open) by means of a passageway 20 70 and port 21.

Slidably mounted in cylinder 18 is a double hollow cylindrical piston 22, the upper end of which contains a helical spring 23 which tends to thrust the piston down in opposition to the 75 suction transmitted from the mixing chamber 3 and mixture outlet 4 through passageway 20. The lower end of the piston 22 is in the form of a cup 24 and contains a smaller piston 25 adapted for reciprocation therein. Depending from piston 25 80 is a hollow stem 26 provided at its lower end with a port 27 and an enlarged head 28 which latter forms a valve controlling a port 29 which establishes communication between the float chamber 12 and passageway 9 to nozzle 6. Within the stem 85 26 is a passageway 30, which, with port 27, establishes communication between float chamber 12 and the interior of cup 24. A lug 31 on the upper face of piston 25 prevents the top of cup 24 from closing the end of passageway 30 when 90 piston 22 is at the bottom of its stroke. A helical spring 32 surrounds stem 26 and bears against the under side of piston 25, thus returning it to the top of its stroke after piston 22 returns to its uppermost position. 95

Communicating with passageway 20 is a lateral bore 33 which leads to the outside of the carburetor and is threaded for the reception of a screw plug 34 and a valve seat 35, as shown in Figure 2. Plug 34 is provided with a central bore 36 which, 100 with an aligned bore 37 in valve seat 35, forms a communication from the passageway 20 to the outside atmosphere through a port 37 in a screw cap 38 which is adapted to engage over the end of plug 34.

Slidably mounted in bore 36 and adapted to engage seat 35 is a valve 39, which allows sufficient clearance in bore 36 to form a free passageway therethrough. The lower end of valve 39 is tapered to fit into and close passage 37 in seat 110

35 when valve 39 is in its lowermost position. The upper end of valve 39 is threaded to engage a plurality of adjusting nuts 40 and 41 which embrace the free end of a thermally responsive element 42, which is fixed to the upper face of plug 34 as with a screw 43. Thermostat 42 is provided with a hole 44 which registers with bore 36 in plug 34 and through which valve 39 passes with sufficient clearance to provide a free passageway from bore 36 to the space enclosed by cap 38.

10 The thermostat 42 is so arranged and calibrated as to raise or lower valve 39 a predetermined amount for each degree change in temperature so that the amount of air drawn through vent 37 15 into passageway 20, to reduce the vacuum therein, is regulated in accordance with temperature by the valve 39.

The operation of my carburetor is as follows: When the vacuum or suction in mixture outlet 20 4 is high and valve 39 is closed, the vacuum acting on piston 22 is approximately equally high and is sufficient to hold piston 22 in its uppermost position as shown in Figure 1. This condition of high vacuum in mixture outlet 4 occurs when the throttle 25 5 is closed (engine idling) and also when the throttle 5 is substantially full open and the engine running at high speed. On the other hand, a condition of low vacuum exists in mixture outlet 4 when throttle 5 is suddenly opened (as when accelerating) and when the throttle is wide open and the engine is running slow under heavy load, and under conditions of low vacuum in mixture outlet 4, the vacuum acting on piston 22 is too weak 30 to hold it in its uppermost position and spring 23 causes it to descend. If piston 22 descends rapidly (as when the throttle 5 is quickly opened) it applies pressure to the liquid fuel in cup 24 and forces piston 25 down, thus opening port 29. Thereupon a liquid fuel accelerating charge is discharged from cup 24 and also from float chamber 12 to nozzle 6. If the piston 22 descends slowly, as when throttle 5 is opened slowly, it applies pressure to the liquid fuel in cup 24 so gently that said fuel escapes therefrom past piston 25 back into 45 float chamber 12 without moving piston 12, so that no liquid fuel is discharged from cup 24 or chamber 12 through port 29.

The foregoing operations have been considered on the basis of valve 39 being closed which is the 50 case only when the carburetor is at its lowest operating temperature and the maximum accelerating charge is desired. If now valve 39 is partly opened, it permits atmospheric air to be drawn into passage 20, and at once reduces the 55 vacuum in cylinder 18 below the vacuum in mixture outlet 4 and the further valve 39 opens, as with increase in temperature, the further the vacuum in chamber 18 is reduced until a point is reached (with valve 39 fully open) where this 60 vacuum is insufficient to retract piston 22 against the force of spring 23. In this case the piston 22 remains at the bottom of its stroke regardless of the position of throttle 5 or the fluctuations in 65 vacuum in mixing chamber 4 and no accelerating charge is delivered when the throttle 5 is suddenly opened. With valve 39 partially open, the 70 vacuum in chamber 18 is only partially reduced

and the output of the acceleration pump is only correspondingly reduced. In this way the amount of accelerating charge is automatically proportioned to the temperature of the carburetor after the thermostat 42 is once correctly calibrated and set.

80 While I have shown and described the preferred form of my invention, I desire it to be understood that I do not limit myself to the constructional details disclosed by way of illustration, as it is apparent that these may be changed and modified by those skilled in the art without departing from the spirit of my invention or exceeding the scope of the appended claims.

85 I claim:

90 1. In a carburetor having a mixing chamber, a vacuum operated acceleration pump, a passageway connecting said chamber and pump, and a thermal responsive air bleed for supplying air directly to said passageway, whereby said pump is rendered inoperative at the highest operating temperatures of said carburetor.

95 2. In a carburetor, a vacuum actuated acceleration pump comprising a cylinder adapted to hold fuel and means separate from said cylinder for modifying said vacuum so that the output of said pump is inversely proportioned to the temperature of the carburetor.

100 3. In a carburetor, a vacuum operated acceleration pump comprising a cylinder adapted to hold fuel and means separate from said cylinder for gradually reducing said vacuum as the temperature of the carburetor increases, whereby the output of said pump is a maximum at the lowest operating temperature of the carburetor and gradually reduced to a minimum at the highest operating temperature of the carburetor.

105 4. In a carburetor, a vacuum actuated acceleration pump comprising a cylinder adapted to hold fuel and thermal responsive means separate from said cylinder for modifying said vacuum so that the output of said pump is inversely proportioned to the temperature of the carburetor.

110 5. In a carburetor having a mixing chamber, an acceleration pump comprising a cylinder adapted to hold fuel and means separate from said cylinder comprising a chamber subject to the fluctuations of vacuum in said mixing chamber and a thermal responsive air valve for modifying said vacuum in accordance with the temperature of the carburetor.

115 6. In a carburetor having a mixing chamber, an acceleration pump comprising a cylinder adapted to hold fuel and a thermostatic needle valve separate from said cylinder for bleeding air into said mixing chamber and modifying the suction actuating said pump in accordance with the temperature of the carburetor.

120 7. In a carburetor having a mixing chamber, an acceleration pump operated by the vacuum in said chamber comprising a cylinder adapted to hold fuel and a thermostatic air valve separate from said cylinder for modifying said vacuum and controlling the output of said pump in accordance with the temperature of said carburetor.

125 AUGUSTIN M. PRENTISS.
